UNITED STATES PATENT OFFICE.

EDGAR E. BROSIUS, OF PITTSBURGH, PENNSYLVANIA.

CONTROLLER.

1,273,142.

Specification of Letters Patent. Patented July 23, 1918.

Application filed November 21, 1917. Serial No. 203,212.

To all whom it may concern:

Be it known that I, EDGAR E. BROSIUS, a citizen of the United States, residing at Pittsburgh, Allegheny county, Pennsylvania, have invented a new and useful Improvement in Controllers, of which the following is a full, clear, and exact description, reference being had to the accompanying drawings, forming part of this specification, 10 in which—

Figure 1 is a side elevation of a controller embodying my invention.

Fig. 2 is a longitudinal vertical section, and

Fig. 3 is a plan view.

My invention has relation to controllers, and more particularly to controllers designed for use where a plurality of fluid pressure operated motive devices are to be 20 controlled from a single operating station.

The object of my invention is to provide a controller of this character which will be simple in its construction, convenient in its mode of operation, and the use of which 25 will greatly simplify the piping connections required.

The nature of my invention will be best understood by reference to the accompanying drawings, in which I have shown a preferred embodiment thereof, and which will now be described, it being premised, however, that various changes can be made in the details of construction, arrangement and combination of the various parts, without 35 departing from the spirit and scope of my invention, as set forth in the appended claims.

In these drawings, the numeral 2 designates an inlet chamber formed within a suitable inclosure, such as that provided by the base and body member 3 and removable cap plate or cover 4. This chamber 2 is provided at one end with an inlet connection 5, which is connected to a source of fluid pressure supply which may be steam, air, water, or other liquid. A bottom wall of the chamber 2 is provided with a plurality of valve seats 6, four of such seats being shown in the present instance. Each of these seats 45 is provided with ports 7 which lead to the pipes 8. These pipes 8 in turn lead to the cylinders of the motive devices (not shown) to be controlled. Three of the seats 6 are shown as having two ports 7, and also an intermediate port 9, while the fourth seat is shown as only having the single port 7, this

representing an instance in which the motive cylinder is supplied with fluid for its operation, and the exhaust, instead of returning to the controller, is to the atmosphere or to some other desired point. 60

Slidably mounted on each of the seats 6 is a valve 10 of the D-type, and which is designed to control the ports. Each of these valves is operatively engaged with an eccentric 11 attached to an operating shaft 12. These shafts extend out to one side wall of the casing and are provided at their outlet ends with suitable actuating means, such as the hand cranks 13. 65

Each of the ports 9 is shown as communicating with an exhaust chamber or passage 14 formed in the base member 3 and having an outlet connection 15 at one end. 16 designates an outlet connection for any water of 75 condensation which may accumulate in the chamber 2, this being especially provided where the controller is used in connection with steam operated motive devices. 70

The operation will be readily understood. 80 The chamber 2 is kept supplied with the working fluid under pressure by the inlet connection 5. With the crank handles 13 in their intermediate or neutral positions (see the two hand cranks at the left hand end of Fig. 1 and the hand crank at the right hand end of said figure) the valves 10 are in position to close both ports 7. When the hand crank is moved to one of the operating positions (shown by the four hand crank in 85 Fig. 1), one of the ports 7 is opened to the admission of fluid pressure from the chamber 2, while the other of said ports 7 is connected with the adjacent exhaust port 9 through the valve 10. Fluid pressure will 90 now be supplied to one end of the motive cylinder controlled by this valve and the exhaust will return through the other port 7, and will be discharged into the exhaust chamber or passage 14. By moving the 95 hand crank in the opposite direction the valve is shifted to reverse the inlet and exhaust connections to the respective cylinders, as will be readily understood. 100

I preferably provide each of the hand 105 cranks 13 with a safety latch or lock of some suitable character. In the drawings, I have shown each crank as provided with a pivoted latch member 17, which is adapted to engage locking recesses 18 on a latch plate 110 19 mounted on the adjacent side wall of the casing. Each of these latch members 17 is

arranged to engage by the action of a spring 17^a, and to be released by means of a push pin 20, mounted in the handle of the crank.

The advantages of my invention will be 5 readily appreciated. The controller is simple in its construction; can be conveniently operated; and in view of the fact that only a single supply and single exhaust connection is required for all the valves, instead 10 of separate supply and exhaust connections for each valve, the piping required is greatly simplified.

In the drawings, I have shown the member 3 as having tapped openings at each end 15 of proper character to receive the supply, exhaust and drain connections, so as to enable the controller to be readily connected up either as a right hand or a left hand controller, those openings which are not in use 20 being closed with plugs. Although I have shown the controller having four valves and arranged to control four separate motive devices, it will be readily understood that I am not limited to this particular number. 25 It will also be obvious that all of the valves may be double-acting, as are the three valves at the left hand end of the figures of the drawings, or that any desired number of them may be single-acting, as in the fourth 30 valve shown.

I claim:

1. A controller for controlling the operation of a plurality of fluid pressure operated motive devices, comprising a casing 35 which is structurally separate from the motive devices to be controlled and which may be positioned at any desired point with respect to said devices, said casing having a pressure inlet chamber therein, one wall of said chamber having a plurality of sets of ports therein, there being one set of such ports for each motive device, a plurality of valves in said chamber, one for each set of ports, said casing having means for the connection therewith 40 of a steam-supply pipe for said chamber, and of pipes communicating with the respective ports for connecting such ports with the motive devices, and a separate actuating device for each valve; substantially as described.

2. A controller for controlling the operation of a plurality of fluid pressure operated motive devices, comprising a casing 55 which is structurally separate from the motive devices to be controlled and which may be positioned at any desired point with respect to said devices, said casing having a pressure inlet chamber therein, one wall of said chamber having a plurality of sets of ports therein, there being one set of such ports for each motive device, a plurality of valves in said chamber, one 60 for each set of ports, the casing having 65 means for making the necessary supply and

port connections, each of the valves having a portion forming the strap of an eccentric, a separate eccentric engaging each such valve portion, and a separate actuating means for each eccentric; substantially as 70 described.

3. A controller for controlling the operation of a plurality of fluid pressure operated motive devices, comprising a casing which is structurally separate from the 75 motive devices to be controlled and which may be positioned at any desired point with respect to said devices, said casing having a pressure inlet chamber therein, one wall of said chamber having a plurality of sets 80 of ports therein, there being one set of such ports for each motive device, a plurality of valves in said chamber, one for each set of ports, and a plurality of valve-actuating shafts, one for each of the valves, 85 said shafts being arranged side by side and projecting out through a wall of the casing, and an actuating crank on each shaft; substantially as described.

4. A controller for controlling the operation of a plurality of fluid pressure operated motive devices, comprising a casing which is structurally separate from the motive devices to be controlled and which may be positioned at any desired 90 point with respect to said devices, said casing having a pressure inlet chamber therein, one wall of said chamber having a plurality of sets of ports therein, there being one set of such ports for each motive device, 95 one for each set of ports, and a plurality of valve-actuating shafts, one for each of the valves, said shafts being arranged side by side and projecting out through a wall of the casing, 100 and an actuating crank on each shaft, together with latch devices associated with said cranks for holding the valves in the desired positions; substantially as described.

5. A controller for controlling the operation of a plurality of separate fluid-pressure operated motive devices comprising a casing, said casing having a pressure supply chamber, one wall of such chamber 115 having a plurality of sets of ports, there being one of such sets for each motive device to be controlled, a plurality of valves seated on such wall, one for each set of ports, a separate actuating device for each 120 of said valves, and pipes connected to the several ports and forming means exterior of the casing for connecting the ports to the motive devices to be controlled; substantially as described.

6. A controller for controlling the operation of a plurality of separate fluid-pressure operated motive devices, said casing having a pressure supply chamber, one wall 125 of such chamber having a plurality of sets 130

of ports, there being one of such sets for each motive device to be controlled, a plurality of valves seated on such wall, one for each set of ports, an actuating shaft for each valve extending out through one side of the casing, a crank on the outer end portion of such shaft, and latch means associated with the cranks for holding the valves in the desired positions; substantially as described.

7. A controller for controlling the operation of a plurality of fluid-pressure operated motive devices, comprising a casing which is structurally separate from the motive devices to be controlled and which may be positioned at a desired point with respect to such devices, said casing having a longitudinally extending pressure supply chamber, a longitudinally extending ex-

haust passage, and a wall separating the chamber and passage, said wall having a plurality of valve seats on its chamber side and a plurality of sets of ports opening through said seats, some of such ports leading into the exhaust passage and the casing having means whereby the other ports may be connected to the motive devices to be controlled, a plurality of separate valves, one for each seat and set of ports, a plurality of transverse actuating shafts for said valves, said shafts being spaced apart longitudinally of the casing, and having separate actuating means; substantially as described.

In testimony whereof, I have hereunto set my hand.

EDGAR E. BROSIUS.
